SCREW CAP

Charles J. Salvo, Somerville, Mass., assignor to
 United-Rexall Drug Company, a corporation of
 Delaware

Application January 3, 1944, Serial No. 516,809

6 Claims. (Cl. 215—43)

1

This invention relates to caps, and with regard to certain more specific features to screw caps for containers such as jars, bottles and the like. The invention relates also to their method of manufacture.

Among the several objects of the invention may be noted the provision of a screw cap made primarily of easily obtainable materials such as cardboard, fibreboard, or the like, which will have a strength and rigidity comparing favorably with that of a metal cap; the provision of a cap of this class wherein the problem of economically incorporating a strong metal thread is successfully met; and the provision of a cap of the class described which lends itself to economical, quantity manufacture. Other objects will be in part obvious and in part pointed out hereinafter.

The invention accordingly comprises the steps and sequence of steps, elements and combinations of elements, features of construction, and arrangements of parts which will be exemplified in the structures hereinafter described, and the scope of the application of which will be indicated in the following claims.

In the accompanying drawing, in which are illustrated several of various possible embodiments of the invention,

Fig. 1 is a side elevation, partly in section showing one form of my new cap applied to a jar;

Fig. 2 is a plan view of a main blank, the dotted circle indicating a score line, and the dotted rectangles the positions of certain inserted thread-forming lugs;

Fig. 3 is a perspective view of a thread-forming lug;

Fig. 4 is a cross section of the Fig. 2 blank after a forming operation and after insertion of a sealing disc, the dotted lines indicating the preliminary formative step of Fig. 2;

Fig. 5 is an enlarged corner detail section of the cap;

Fig. 6 is a plan view of an alternative form of lug-supporting band; and,

Fig. 7 is an enlarged detail of an alternative form of cap employing said band of Fig. 6.

Similar reference characters indicate corresponding parts throughout the several views of the drawing.

Referring now more particularly to Fig. 1, there is shown for example at numeral 1 a glass jar having a molded male thread 3 with which the female thread of the cap is to cooperate.

Fig. 2 shows a flat circular blank 5 which forms the main body of the cap. This is provided with radially extending tabs 7 between which are relieving notches 9. The tabs 7 lie outside of a circular score line 11. The blank is composed of cardboard, fibreboard, or the like. The central portion 5 and tabs 7 are integral.

Punched into the tabs 7 are lateral slits 13. These are located successively at increasing radial

2

distances on adjacent tabs. The tabs are equally spaced, as indicated, and the radial distances from the center of the blank to the slits increases by equal increments between successive tabs. The result is an equi-angular spiral of slits (Fig. 2).

Thus, when the tabs 7 are turned up at right angles to the central portion of the blank so as to close the notches 9 and form an inner annular layer or cylindric skirt, the slits 13 take up positions on a helical locus within said cylindric skirt (Fig. 4). The tabs 7 are preferably not turned up until thread-forming lugs 15 are inserted into the slits 13, as indicated by the dotted lines in Figs. 2 and 4.

Each lug 15 comprises a deformable preferably metal strip which is crimped to form a double-thickness hairpin-shaped flange portion 17 at the foot of which are oppositely extending coplanar pads 19 and 21. One pad 19 is preferably longer than the other pad 21. The total thickness of the layers forming the flange 17 is only slightly greater than the width of the slit 13. The lateral length of each flange 17 is about equal to that of a slit 13. Thus the lugs 15 may be applied to the blank 5 by inserting the flanges 17 through the slits 13 wherein they are frictionally held. The pads 19 and 21 are then located beneath the tabs 7 prior to turning said tabs up into their cylindric relationship. Insertion of the lugs is quite simple to perform en masse by circularly relating them in a suitable jig or fixture as required by the locations of the slits 13 in the blank, and then forcing the blank down over the positioned lugs so that the slits are forced over the flanges 17. Other means for inserting the lugs may, of course, be used.

The purpose of making the coplanar pads 19 and 21 of unequal lengths is so that they may be positioned, in the case of the outermost slits 13 to prevent extension of the lugs beyond the tabs, and in the case of the innermost slits 13 to prevent extensions of the lugs within the score line 11. To accomplish this it is only necessary to invert the radial relationship of the pads 19 and 21 as indicated at the left and right respectively at Fig. 2.

After the lugs have been inserted as indicated by the dotted lines of Fig. 4, the lug-bearing tabs 7 may be turned into the cylindric position shown by the use of a suitable bending die or the like. It is preferable that before turning up the tabs 7 a sealing disc 23 be applied to the blank so that it becomes located within the discontinuous helical thread formed by the lug flanges 17.

Next, in order to hold the tabs 7 in the cylindric relationship shown, there is slipped over the outside of the tabs 7 and the exterior of the pads 19 and 21 a cardboard or similar ring indicated at numeral 25 and forming an outer annular layer. This ring may be made up in various ways but a preferable one is to cut it from a pre-

formed, convoluted-wound cylinder. The layers, due to the preliminary convolute winding, are indicated at 29. Some adhesive 30 is applied between the skirt formed by tabs 7 and the ring 25 in order to hold the parts together axially and more firmly to anchor the lugs 15. Then a paper cover 31 may be applied, lapped over as indicated at 33, and the top of the cap finished with another circular paper cover shown at 35. The covers 31 and 35 may be decorative.

The result is a strong and rigid cap of neat appearance wherein only a very small amount of metal is used. It will be understood that if desired the lugs 15 may be made of fibre, plastic or other suitable material. The discontinuous character of the thread is not detrimental to proper cooperation with the male thread 3 on the jar and at the same time it saves material that would be otherwise used to make the thread continuous.

It is to be understood that the ring 25 snugly fits the outside of the members which it encircles so as to resist any expansive strain. Thus also tilt of pads 19 and 21 is resisted. If desired ring 25 may be wrapped on (in situ), rather than being pre-wound.

An advantage of forming the lugs as indicated with the double-layered flange 17 and the smooth, rounded edges 18, is that said edges form a desirable type of engagement at the root of the thread 3.

In Fig. 6 is shown a modification in which a cardboard, fibre or like strip 37 is provided in its flat condition with slits 39, arranged on a bias but individually parallel to the length of the strip. Into these slits 39 are inserted the lugs 15 as indicated, the lugs being reversed at a suitable central point on the strip to avoid extension of any pad 19 or 21 from a lateral edge of the strip.

The strip 37 is then wound into a cylinder or band with the extending flanges 17 directed inward to form the desired discontinuous thread. This thread-bearing ring is then inserted into the flanged portion 41 of an ordinary drawn or like cap 43 and forms an inner annular layer therein. A drawn cap is for example made simply by pushing the central portion of a circular blank through a drawing die so as to form a skirt of its edge portion. The skirt is part 41 in Fig. 7 and forms an outer annular layer. Adhesive 32 is used between parts 41 and 37 thus anchoring them and the lugs 15. It is to be understood that before inserting into drawn cap 41, 43 the thread-bearing ring (formed of the lug-bearing strip 37), a suitable sealing disc 45 is inserted. An exterior band 47 is then applied as above-described in connection with the band 25. This band 47 is also provided with a suitable decorative cover 49 if desired and on the top of the cap is another suitable cover 51. Unlike the cover 31, the cover 49 is not laid over beneath the cover 51 on top of cap 43. This is optional.

In view of the above, it will be seen that the several objects of the invention are achieved and other advantageous results attained.

As many changes could be made in the above constructions without departing from the scope of the invention, it is intended that all matter contained in the above description or shown in the accompanying drawing shall be interpreted as illustrative and not in a limiting sense.

I claim:

1. A cap comprising a member formed integrally of a circular part and axially directed tabs, slits in the respective tabs successively positioned at increasing distances from the circular part, lugs cooperating with the slits, each lug comprising a crimped strip forming a double-layered flange extending through a slit, the remainder of each lug forming co-planar pads engaging the outside of a tab, and a constraining band formed around tabs and engaging all of said pads.

5. A cap comprising a member formed integrally of a circular part and axially directed tabs cooperating circularly to form a skirt, slits in the respective tabs successively positioned at increasing distances from the circular part, lugs cooperating with the slits, each lug comprising a crimped strip forming a double-layered flange extending through a slit and forming co-planar pads of unequal lengths engageable with the outside of the skirt, the relationship of the pairs of unequal pads of some lugs being reversed with respect to those of others, and a band formed around said skirt and engaging all of said pads.

10. A cap comprising a member formed integrally of a circular part and axially directed tabs cooperating circularly to form a skirt, slits in the respective tabs successively positioned at increasing distances from the circular part, lugs cooperating with the slits, each lug comprising a crimped strip forming a double-layered flange extending through a slit and forming co-planar pads of unequal lengths engageable with the outside of the skirt, the relationship of the pairs of unequal pads of some lugs being reversed with respect to those of others, and a band formed around said skirt and engaging all of said pads.

15. A screw cap comprising a drawn cup having a cylindrical skirt, a holding band outside of and engaging said skirt, a lug-holding strip formed cylindrically inside of said skirt, said strip having openings formed on a path which is at a bias to the length of said strip, and lugs having extensions directed radially inwardly through said openings and holding portions located between and engaged by the strip and the skirt, said extensions fitting tightly in said openings to prevent shifting movements of said lugs, said skirt preventing radial and tilting movements of said lugs.

20. A screw cap comprising a cup-shaped member including a cylindric part having an outside wall surface and spaced slits through said cylindric part, the slits lying substantially along a helical path on said cylindric part, lugs having flat flange portions extending through the slits and pad portions lying on said outside wall surface, and enclosing banding means attached to the outside wall surface of said cylindric part and engaging said lugs to anchor them against radial and tilting movements.

25. A screw cap comprising a cup-shaped member having a cylindrical wall, said wall including an inner annular layer having a plurality of slits therein spaced substantially along a helical path, lugs having hairpin-shaped portions extending through said slits and oppositely directed coplanar pad portions engaging the outer periphery of said inner annular layer, said cylindrical wall including an outer annular layer surrounding said inner annular layer and engaging said pad portions and confining said lugs in said slits to prevent radial and tilting movements thereof, said hairpin-shaped portions fitting tightly in said slits to prevent shifting movements thereof.

30. A screw cap comprising a drawn cup having a cylindric skirt, a holding band surrounding and engaging said skirt, a lug-holding strip formed cylindrically inside said skirt, said strip having slits therein on a path which is at a bias to the length of said strip, and lugs having extensions directed radially inward through said slits and holding portions located between and engaged by said strip and said skirt, each lug having a crimped portion forming the said extension, said crimped portion comprising a double-layered flange having a rounded end, the remainder of each lug comprising coplanar pads forming said holding portions.
